UNITED STATES PATENT OFFICE

2,458,454

ELECTRONIC CONTROL APPARATUS

Anthony Winther, Kenosha, Wis., assignor to
Martin P. Winther, trustee, Waukegan, Ill.

Original application May 4, 1944, Serial No.
534,111. Divided and this application April 29,
1946, Serial No. 665,884

1 Claim. (Cl. 315—141)

1

This invention relates to electronic control apparatus, and with regard to certain more specific features, to electronic rectifier tube control means.

This application is a division of my United States patent application Serial No. 534,111, filed May 4, 1944, for Electronic control apparatus, and relates particularly to the current rectifier means disclosed in said application.

Among the several objects of the invention may be noted the provision of improved means for firing electronic tubes so as to effect a great saving in tube life and avoid erratic action thereof; the provision of means of the class described whereby control of the tubes is made much more accurate; and the provision of means of this class which minimizes unbalanced conditions of firing load between several tubes. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claim.

In the accompanying drawings, in which is illustrated one of various possible embodiments of the invention,

Fig. 1 is a wiring diagram of a control unit embodying the invention;

Fig. 2 is an illustrative diagram but not to scale of the wave actions of certain rectifier tubes; and,

Fig. 3 is a diagram similar to that of Fig. 2 showing the results of certain resistance adjustments.

Similar reference characters indicate corresponding parts throughout the several views of the drawings.

In Fig. 1 is shown a wiring diagram of the contents of a circuit used in certain control units used in the parent application. This circuit has seven main divisions as follows:

- (1) A principal D. C. rectifier circuit I;
- (2) A main or basic voltage supply circuit II with the usual filters and regulators for maintaining constant voltage;
- (3) A tilting bridge circuit III;
- (4) A manually controlled adjustable reference voltage circuit IV;
- (5) An auxiliary machine-speed-controlled reference voltage circuit V;
- (6) A clutch speed control circuit VI; and
- (7) A clutch torque control circuit VII.

2

Circuits IV and V (adjustable D. C. networks) are connected in voltage aiding sequence and so are circuits VI and VII (adjustable D. C. networks), but the voltage sum from IV and V, and 5 voltage sum from VI and VII, are arranged for voltage opposition. Also, circuits V and/or VII may at will be cut out without changing the opposition relation of the residual voltages. How this may be done will appear.

10 Referring to the principal rectifier circuit I, similar ones have been described in my Reissue Patent 22,432, dated February 1, 1944, and in Patent 2,277,284, dated March 24, 1942. This circuit I consists of a transformer T—1 having a primary winding connected across the lines L—2 and L—3 of the A. C. circuit. The secondary S of this transformer T—1 is connected at its opposite ends to the anodes of a pair of three-element, hot cathode, gas-filled, grid-contro'led 15 rectifier tubes 1 and 2 of the half-wave type. These tubes require proper grid potential to fire. They are characterized by the fact that the grid of each tube can start the anode current, but cannot shut it off. However, when the alternating anode voltage passes through zero, the current dies out automatically. The effect of the 20 grid action is to start the respective tube firing at one point or another on one swing or firing loop of the A. C. anode voltage wave. Different 25 total average D. C. currents are passed as determined by the grid actions. A two-anode control or amplifier tube 3 in the tilting bridge circuit III effects alternate firing of tubes 1 and 2, its anodes being respectively connected with the grids of 30 tubes 1 and 2.

A mid-tap 12 of the secondary S is connected to one end of the field coil CL of a slip clutch EC—2. The coil CL is in the slip clutch EC—2 which has been diagrammed at the lower part of 40 the figure. The electrical network between the anodes and cathodes of tubes 1 and 2 including the D. C. load coil CL, may be referred to as an A. C. potential circuit. To avoid diagram complexities, the coil CL has been shown twice. In 45 the upper part of the diagram it is located in the circuit and in the lower part its mechanical location only is indicated with respect to the field member F—2, without showing it in the circuit.

The other end of the field coil CL is connected 50 to the mid-tap 13 of a transformer T—2, the primary of which is connected across lines L—1 and L—2. The opposite ends of the secondary of the transformer T—2 are connected in parallel with the cathodes of the respective tubes 1 and 2. 55 Control of the tubes 1 and 2 is managed by means

of grids G-1 and G-2, respectively. Resistances R-1 limit the current flowing through the grids so that they are substantially voltage controlled from the anodes of tube 3. When the tubes 1 and 2 fire (which occurs alternately, as will appear), the anodes alternately feed D. C. current to opposite ends of the secondary S. Thus direct current flows from the center tap 12 of the transformer T-1 through the coil CL and to the center tap 13 of the transformer T-2.

Alternating current applied to circuit I from the secondary of transformer T-2 proceeds to the cathodes of the tubes 1 and 2 and is rectified to produce said D. C. current. The transformer T-2 is connected 120° out of phase with respect to the transformer T-1, being connected across L-1, L-2. The effect of this in connection with other parts of the circuit will appear.

In view of the above, it will be seen that the secondary S of transformer T-1 applies an alternating voltage to the anodes of the tubes 1 and 2. Whenever the grid G-1 and anode of the tube 1 are positive enough, its cathode passes current toward the anode and through the clutch coil CL. Thus this tube becomes a half-wave rectifier. The action of the tube 2 is similar, but alternating with respect to the action of tube 1. The solid arrows in Fig. 1 illustrate an exemplary flow of electrons when they occur through tube 1.

As stated, circuit II is a main reference voltage circuit. By its means, reference voltage is established for setting a main level of potential for controlling the grids of the principal rectifier tubes 1 and 2. This reference voltage circuit II originates in a secondary component of a transformer T-5, the latter being fed from the lines L-1 and L-2. Rectified negative current under a given voltage issues from the cathode of tube 5, induced by the action of the transformer T-5. The cathode is heated by connection XX from a secondary component of a cathode supply transformer T-3, the latter being fed from the lines L-2 and L-3. Thus voltage is applied from the mid-tap of T-5 through points 29, 30 and then to point 17. Here the circuit splits, part of the voltage being applied through resistance R-5, and part being applied to the cathode of the amplifier tube 3. The heating element of the cathode of tube 3 is connected to a secondary component ZZ of said transformer T-3. Thus voltage is impressed upon the anodes of tube 3 and the circuit is completed to tube 5 via resistances R-2, R-3, points 15 and 31, resistance R-6 and choke K-1, back to the cathode of tube 5. The circuit is completed, as indicated by the solid arrows in Fig. 1, whenever tube 3 fires an anode.

Condenser C-1, cold cathode tube 4, resistance R-6 and choke K-1 are related so as to effect filtering and regulation to maintain constant voltage conditions in circuits II and III. Tube 4 acts as a voltage regulating leak. Details of this type of voltage regulation have also been specified in my U. S. patent application Serial No. 519,783, filed January 26, 1944 (issued as Patent 2,411,122).

Resistance R-5 is connected with resistance R-4 at point 14. Resistance R-4 connects with point 15. The mid-tap 13 of the transformer T-2 is connected with the point 14 between the resistances R-5 and R-4. Resistances R-5, R-4, the tube 3, and the resistances R-2 and R-3 considered alternatively, constitute a bridge

through which voltage on grids G-1 and G-2 is applied.

The rectifier tube 3 has grids G-3 and G-4 controlling flow of negative electrons to its respective anodes and the respective anodes feed the grids G-1 and G-2 of the rectifier tubes 1 and 2 respectively, resistances R-1 being used in the circuits of the said grids G-1 and G-2. Thus when either of the grids G-3 or G-4 is relatively negative with respect to the cathode of tube 3, the firing of the latter is suppressed to the respective anode. When either of these grids is relatively positive, the tube 3 fires to the respective anode. When tube 3 fires, this increases the negative electrons in grid G-1 or G-2 of tubes 1 or 2, tending to suppress firing of the relevant one of these tubes. When grid G-1 or G-2 is starved of negative electrons, that is, when the relative part of tube 3 does not fire, then the respective grid G-1 or G-2 becomes relatively positive and the relevant tube 1 or 2 fires. In short, tubes 1 and 2 respectively tend to fire when the relevant anodes of tube 3 do not, and vice versa.

The grids G-3 and G-4 of tube 3 are supplied through resistances R-14 from the secondary of a transformer T-4. The primary of a transformer T-4 is energized from the cathode circuit supplied by transformer T-2. The circuit from the grids G-3 and G-4 through transformers T-4 and T-2 to lines L-1 and L-2 may be conveniently termed an A. C. network. The firing voltage for the grids of the principal tubes 1 and 2 is also amplified through the tube 3 which is of the proper type for the purpose.

The transformer T-4 imposes on the grids G-3 and G-4 of the amplified tube 3 sinusoidal voltages phased 180° apart, which also are respectively 120° out of phase with the respective voltages applied to the anodes of the tubes 1 and 2, because transformer T-4 receives its primary supply from the secondary of transformer T-2. It will be noted that transformer T-2, which supplies T-4, is connected across wires L-1 and L-2 of the A. C. line, and transformer T-4, which affects tubes 1 and 2, receives its supply from lines L-1 and L-3. As will be shown, the sinusoidal voltages on 3 are voltage rider waves on an adjustable D. C. control potential applied from circuits IV, V, VI and VII to point 18 of T-4. Thus the major portions of the waves applied to grids G-1 and G-2 will be fairly flat, as will appear. Since the anodes and cathodes of tube 3 are connected across the reference voltage of the circuit II, a D. C. current similar in shape to a half-wave rectified current is drawn from the system II, the waves being controlled alternately by the grids G-3 and G-4. Since the actions of the grids G-3 and G-4 alternately make each half of the tube 3 a half-wave rectifier, it will be seen that each anode of the tube passes current alternately in accordance with the A. C. potential developed by the transformer T-4. Hence the form of the D. C. current furnished by the circuit II through each anode of tube 3 is that of a current shaped in accordance with the wave of transformer T-4. Thus a firing action occurs alternately on the anodes of tube 3 and this firing will affect the grids G-1 and G-2 alternately and independently. Tube 3 is heated through connection Z-Z with T-3.

Since the principal tubes 1 and 2 can each be fired only when its appropriate anode voltage is positive, the firing must be and is done dur-

ing that time for each tube. The anode sine waves 101, 102 (Fig. 2) applied to tubes 1 and 2 are shown, the one for tube 1 as a solid line, and the one for tube 2 as a dash line. The firing voltage of tube 1 is represented by dotted lines 103, and it will be noticed that these dotted lines 103 reappear in succeeding cycles under 101. Dotted lines 104 represent the corresponding firing voltage line in the succeeding cycles belonging to tube 2. Therefore the dotted lines show the grid voltages which would be necessary to fire the tubes 1 and 2. Lines 103 and 104 for matched tubes are nearly the same but some variations are to be expected. The dot-dash line 106 represents the cusped but otherwise fairly flat D. C. voltage wave induced by the combination of the D. C. reference voltage on point 18 of transformer T-4, and the A. C. voltage applied to grid G-3 of tube 3 by this same transformer T-4. Double-dot-dash line 107 is the corresponding line for grid G-4. The D. C. lines 106 and 107 each come to a peak once under each positive loop of lines 101 and 102 respectively.

It will also be noticed that waves 106, 107 are inverse to the waves 101, 102 applied to tubes 1 and 2, and represent a series of half-wave type D. C. conditions. These waves 106 and 107 may be shifted up and down by adjusting a resistance R-8a (to be described) to effect various firing intersections with lines 103 and 104. This shifts the basic D. C. potential component line L, which represents the D. C. control voltage at 18 of T-4. Fig. 3 illustrates the result of such a shift. Wherever (Fig. 3) the adjustable firing voltage curves 106, 107 intersect the grid-firing voltage curves 103 and 104, the tubes 1 and 2 will be fired (see the cross-hatched areas), and since the cusps or crests of the curves 106 and 107 are relatively steep and can be made even steeper than illustrated on the drawing, it is possible to sweep these curves through the entire lateral ranges of the firing voltages 103 and 104 much more effectively and with more definite control of the firing point of the tubes. Fig. 3 illustrates the maximum upward adjustment of L and full firing of tubes 1 and 2. By using the cusps or crests of the waves 106, 107 to intersect the broad inverted crests of the grid-firing voltage curves 103, 104 and by inverting in respect to the anode voltages 101, 102 applied to tubes 1 and 2, the action is such as to eliminate any effect of one firing voltage peak on another.

It is to be understood that the lines 106 and 107 diagrammatically indicate the conditions above mentioned and that there may be minor variations in the particular wave forms which carry out the stated principles. The important principle is that wherever either curve 106 or 107 intersects grid-firing voltage curve 103 or 104, respectively, to effect firing, the respective curve 106 or 107 is concave upward.

Hence all tendency for so-called wave overlap in tubes 1 and 2 (such as occurred in older systems) is eliminated. A great saving is effected in tube life and erratic action avoided such as was heretofore caused by different "grid-firing voltage curves" of different tubes. In other words, the major portions of the curve of the firing voltages 106 and 107 are flat, with the cusps as desired. Thus it is not possible, as heretofore, for the applied A. C. firing voltage substantially to intersect the entire firing voltage at once which with improperly matched tubes would cause one to assume a substantial overload.

Tests made with this equipment indicate that

the control of the tubes is much more accurate than by the use of a broad 90° firing control wave with a curving and gentle top, as previously used. This is because the two tubes 1 and 2 in the 5 single-phase circuit are fired substantially equally due to the steepness of the approach between pairs of curves such as 106, 103; 107, 104. Unlike the old scheme, differences in tube "grid-firing voltage curves" such as 103 and 104 will result in very little unbalance of firing load carried by tubes 1 and 2.

The mid-tap 18 (Fig. 1) of the secondary of the transformer T-4 is connected with circuit VII at 19 and the mid-tap of transformer T-5 is 15 connected with the circuit IV at 28. Circuits IV and V operate in voltage aiding sequence with the voltage from point 29. The circuit IV is a manually adjustable reference voltage circuit and the circuit V is an auxiliary reference voltage circuit.

Circuit IV has a supply transformer T-6 which is energized from wires L-1 and L-2 of the A. C. circuit. Circuit V is energized from a transformer T-1, the primary of which is energized from the 20 A. C. generator GN-1.

In detail, circuit IV consists in a rectifier tube 1, the anodes of which are connected with said transformer T-6 energized from line wires L-1 and L-2. The center tap of this transformer 30 T-6 connects with potentiometers R-8 and R-8a. Potentiometer R-8 is of the fixed type and point 26 is placed in such a position on R-8 with respect to point 27 that a desired minimum voltage will be obtained when the circuit V is 35 cut out of action. The resistance R-8a includes a manually controlled tap 26a for manually controlling the voltage taken from the circuit IV. A switch SW-3 having three components has a normally closed contact at 28 and two normally 40 opened contacts at 29a and 30a. When the two normally opened contacts 29a and 30a are closed and the normally closed contact 28 is opened, resistance R-8 is removed and resistance R-8a is substituted. On the other hand, when the contacts at 29a and 30a are opened and the one at 45 28 is closed, then the resistance R-8 is effective and the resistance R-8a is cut out. The circuit IV from points 28 or 29a is completed through the resistance R-7, choke K-2 and through the 50 cathode of the tube 1. A condenser C-2 and cold cathode tube 6 serve to maintain constant voltage conditions in this circuit.

In detail, circuit V originates at the anodes of tube 8, being completed through the secondary 55 of transformer T-7, point 23, variable resistance R-9, point 24, choke K-4 and the cathode of tube 8. A condenser C-3 serves the usual filtering purposes in association with the choke K-4. A switch SW-1 has a normally open 60 contact 31 and normally closed contact 32. By closing contact 31 and opening 32, the output lead LD of the circuit IV is connected directly to the terminal 22 of circuit VI. This isolates circuit V. Tube 8 is heated through connection YY 65 with transformer T-3.

As stated, the voltages from circuits IV and V and from point 29 oppose the voltage generated by the circuits VI and VII or by one of them. These voltages from IV, V and 29 all are directed 70 to point 22 and pass from that point to the grids G-3 and G-4 of tube 3 via resistance R-10, point 21, variable resistance R-11 (or switch element SW-2-a), mid-point 18 of transformer T-4, resistances R-14 to the grids G-3 and G-4 of tube 3. In Fig. 1 the voltage effects

from point 29 to 22 are shown by dashed arrows. Beyond point 22, to the right and to 18, the sum of the voltage effects from IV, V and 29 is indicated by dot-dash arrows.

In detail, circuit VI is constituted by a rectifier tube 9, the anodes of which are connected to the secondary of a transformer T-8. The primary of the transformer T-8 is supplied by a variable voltage generator GN-2 driven from the field member F-2 of clutch EC-2, for example. Voltage from the mid-tap of the secondary of transformer T-8 is supplied to point 22 in opposition to the voltage from circuits IV and V. The circuit VI is closed through resistance R-10, point 21 and the cathode of tube 9. The condenser C-4 is used for the usual filtering purpose. Local circulation is shown by the wavy arrows. The heater element of the cathode of tube 9 is fed from connection YY of the secondary of the cathode transformer T-3. Thus the circuit VI, like the circuit V, does not depend for energization upon the A. C. line, but upon the speed of an independent generator, namely GN-2.

In detail, the circuit VII is constituted by a rectifier tube 10, the anodes of which are connected to the secondary of a transformer T-9. The middle tap of a secondary of this transformer T-9 is connected to point 20, the circuit being completed through resistance R-11, point 19, to the cathode of the tube 10, the condenser C-5 serving filtering purposes. Local circulation is here also shown by wavy arrows. The voltage of circuit VII is in the same sequence with the voltage from circuit VI, and the sum of these two voltages is in opposition to that from the sum of the sequence voltages from the circuits IV and V and point 29. Point 19 of the circuit VII is connected to the mid-tap 18 of the secondary of transformer T-4 through a normally closed element b of a switch SW-2. This switch element is by-passed by a normally opened element a of the same switch SW-2. Thus circuit VII may be isolated by opening the switch element b and closing the switch element a. Tube 10 is heated from YY of T-3.

The primary of the transformer T-9 is energized from the A. C. circuit through means adapted to provide a voltage from circuit VII which is substantially a straight-line function of the torque delivered by the A. C. motor WM. This is accomplished by means of a current transformer T-10 having a primary in the line L-3 and a secondary which feeds the primary of the transformer T-9. Resistance R-15 is connected across the secondary of the transformer T-10. This provides a load.

Voltage transformer T-11 has its primary connected across the lines L-1 and L-2 of the A. C. circuit. Resistance R-13 is connected across its secondary and has a variable tap 33 connected to the secondary of transformer T-10. Point 34 of transformer T-11 is connected to the variable tap 32 of a resistance R-12. By a suitable adjustment of the resistances R-12 and R-13, the transformer T-11 can be caused to buck down that component of current generated in the transformer T-10 as is caused by the magnetizing requirements of the motor WM. The transformer T-11 is so connected and 32 70

and 33 are so adjusted that the voltage generated by T-11 cancels the voltage generated by the transformer T-10 when the motor is idling. Thus the load-ampere curve of the motor is substantially a straight line and the effect is to correct for power factor. The circuit between transformers T-9, T-10 and T-11 may be referred to as a transformer circuit component in governing circuit VII for obtaining a straight-line relationship between the voltage on T-9 and torque on the motor WM. Potentiometer R-13 is the one that bucks out magnetizing current and R-12 changes the slope of the straight-line voltage-current relationship. This feature is claimed in my copending U. S. patent application Serial No. 655,699, filed March 20, 1946, for Control apparatus, said last-named application being also a division of said parent application Serial No. 534,111, mentioned above.

Commercial designations for the various tubes that are useful in the various locations are as follows:

Tubes 1 and 2 EL C6 J
Tube 3 6N7

Values of other items in the circuit are designated on the drawings.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

Tube firing control apparatus for at least one gas-filled rectifier tube having an anode, a cathode and a grid, comprising an A. C.-potential circuit including a D. C. load and connected across said cathode and anode, the current of which circuit is rectified by said tube to feed said load, an adjustable D. C. network adapted to produce an adjustable D. C. potential component, a control tube having an anode non-inductively connected with the grid of said rectifier tube and having a grid connected to said adjustable D. C. network, an A. C. network having a potential in fixed out-of-phase relation to the A. C. potential impressed upon the anode of said rectifier tube, said A. C. network being also connected to said grid of the control tube, whereby the grid of the rectifier tube is supplied by the anode of the control tube with an adjustable firing voltage composed of an adjustable D. C. component and a fixed A. C. component undistorted between the said tubes.

ANTHONY WINTHER.
